METHODS AND COMPOSITIONS FOR CONTROLLING FIRES

George A. Connell, Los Angeles, Calif., assignor to United States Borax & Chemical Corporation, Los Angeles, Calif., a corporation of Nevada

No Drawing. Application March 29, 1957
Serial No. 649,291

14 Claims. (Cl. 169—1)

This invention has to do with methods and compositions for controlling fires.

Whereas, the invention is useful for many different types of fire control, it is especially effective as an aid in checking or preventing the spread of fires.

An important purpose of the present invention is to provide means and methods for treating solid fuel in the path of a fire to reduce its flammability and thereby to facilitate checking the spread of the fire.

A particular advantage of the invention is that it is well adapted for treating fuel far in advance of a fire as well as fuel that is actively burning.

The term "solid fuel" in the present specification and claims embraces in particular all types of vegetation, including light brush, leaves, and grass, as well as heavy branches and tree trunks; and also includes other solid combustible materials, such as are commonly involved in structural fires.

In controlling fires in many types of fuel, particularly in the presence of strong winds, it is often difficult or impossible to attack the fire directly where it is burning intensely. That is especially true of fires in forests and in thick brush and scrub growths, such as abound in the southwestern part of the United States. Under such conditions it is highly desirable to limit the spread of the fire. That is sometimes attempted by clearing away the fuel from an area in the path of the fire. However, to be effective, such clearing must be fairly complete within a strip of appreciable width. Once a fire has started it is usually difficult or impossible to prepare such a cleared strip rapidly enough to be effective.

Previously available methods for treating fuel to reduce its flammability have been relatively ineffective for the present purpose. For example, spraying the fuel with water in advance of a fire may be beneficial for a short time, but the water tends to evaporate rapidly, particularly as the fire approaches. That is especially true under conditions of high wind and/or low humidity, which often accompany dangerous fires.

Numerous chemical formulations have been proposed for treating special materials, such as fabrics, wall-board and the like, to reduce their flammability. However, the expense of most such formulations prevents their use on a large scale. Moreover, the application of such formulations frequently requires a succession of distinct steps, sometimes separated by definite time intervals, for example to permit drying. And many such previously known treatment compositions are effective only if the treated material is deeply penetrated by the chemical formulation. Such penetration is not attainable with many types of fuel that cause serious fire hazards.

Among the more specific objects of the present invention are to provide a relatively economical composition which is effective to reduce flammability of a wide variety of solid fuels, including those typically involved in structural fires as well as all types of vegetation; which is effective when applied primarily to surface areas of the

fuel; and which becomes effective immediately upon application and remains fully effective thereafter at least for a period of hours or days.

In accordance with one aspect of the invention, fuel in the path of a fire is coated with an adherent layer consisting essentially of solid calcium-containing borate. The borate layer may also contain any suitable type of binder and may, if desired, include other fire-retardant ingredients. Relatively minor proportions of further additives, such as will be typically described, may also be included. I have discovered that such a layer of calcium-containing borate can be formed on surfaces of solid fuel of substantially any type by applying to the fuel a suspension of solid finely divided borate particles in an aqueous medium.

It is preferred to include in that suspension a suitable stabilizing agent to render the suspension stable during storage and transportation. Preferred stabilizing agents are those which render the suspension thixotropic; and which also act as a binder for the borate particles after application of the suspension to the fuel.

An important advantage of the present invention is that the concentration of active fire-retarding agent in the treating composition is not limited, as in many previously available fire-retardant compositions, by considerations of solubility. Hence the low solubility in water of calcium-containing borates does not prevent their effective application to the fuel by the methods of the invention. That is accomplished by applying the borate in the form of an aqueous suspension, rather than as a solution.

The compositions of the invention may be employed in a wide variety of ways. They are particularly useful for application to fuel in the path of a fire to check its spreading. Since such application may be made rapidly and becomes effective immediately, the invention is particularly valuable for checking the spread of existing fires. However, the compositions of the invention may also be usefully applied in the path of a potential fire. For example, in carrying out controlled burning of vegetation in a definite land area, of slashings from logging operations and the like, a strip of fuel bounding the area to be burned may be treated in advance to aid in confining the fire to the intended area.

In accordance with a further aspect of the invention, aqueous suspensions of calcium-containing borate are applied to fuel in the path of a fire either closely in advance of the fire or while the fuel is already actively burning. That type of application, which may often be made advantageously from aircraft, is particularly well adapted for controlling forest fires in which the upper branches of trees are burning. Such fires are commonly known as crown fires and are particularly difficult to control with previously available methods.

In the present specification and claims the phrase "in the path of a fire" includes potential as well as existing fires, and includes not only portions of the fire path well in advance of any existing fire, but also portions that are already burning.

A particular advantage of the calcium-containing borate coatings of the invention for the present purpose is that they are very light in color, typically white or substantially white. That fact provides a distinctive appearance of treated areas, showing clearly which areas have been treated and which have not. It also facilitates observation of the degree of coverage that has been attained, permitting maximum economy of material without sacrifice of effectiveness. That is especially important in combatting fires in remote locations, where economy of material is often critical.

One illustrative calcium-containing borate that may be

employed in the invention is the sodium-calcium borate that corresponds essentially to the formula

Sodium-calcium borate of that type is available, for example, as a naturally occurring mineral known as ulexite. Ulexite is mined especially in Kern County, California, and is also imported from Chile. Ulexite is known both in massive form and in a filamentary form known as cottonball.

Another illustrative calcium-containing borate is the calcium borate that corresponds essentially to the formula $\text{Ca}_2\text{B}_6\text{O}_{11} \cdot 5\text{H}_2\text{O}$. Calcium borate of that type is available as the naturally occurring mineral known as colemanite, which is mined, for example, in Inyo County, California.

A further example of calcium-containing borate, which is particularly convenient and effective for the present purpose, is a type of natural ore that is essentially a mixture of colemanite and ulexite and contains also an appreciable proportion of insoluble gangue material. Natural ore of that type is mined, for example, at Shoshone in Inyo County, California. For convenience of description, that type of ore will be referred to herein as Shoshone ore, but without implying any limitation as to actual origin. A typical variety of such Shoshone ore contains substantially 58% ulexite, 23% colemanite and the remainder insoluble gangue. The borate components of such ore may thus be characterized as sodium oxide, calcium oxide and boron trioxide in an overall relative ratio approximating 1:3:8, respectively, by weight. The insoluble gangue of Shoshone ore is useful in aiding formation of an aqueous suspension of the ore and in stabilizing the resulting suspension, but, from the standpoint of the direct fire retarding action of the resulting coating on the fuel, the gangue is not an essential component of the composition.

It is desirable that the calcium-containing borate be finer than about 50 mesh. Superior results are obtained when it is ground to such a relatively fine mesh size, for example, that about 80% of the material will pass a No. 200 U. S. Standard screen. When coarser material is used it is preferred to exclude any particles larger than about 50 mesh, both to avoid risk of clogging the spray nozzle and because larger particles reduce the strength and adherence of the resulting coating on the fuel.

In accordance with the invention, calcium-containing borates such as those illustratively described can be applied to surfaces of fuel as an aqueous suspension and is then immediately appreciably more effective than a corresponding weight of water for checking a fire. Moreover, upon evaporation of the liquid water, such an aqueous suspension will form a solid, hard and remarkably durable coating. That coating layer has been found to greatly reduce flammability of the fuel. That result is particularly striking when the fuel is exposed briefly to a very hot fire, as typically occurs, for example, in wild brush and forest fires.

Such reduction in flammability of fuel is obtainable with suspensions of calcium-containing borate over a wide range of borate concentrations. In general, effective results may be obtained with compositions comprising from about 2 lbs. to as much as 10 lbs. or more of calcium-containing borate per gallon of water. For any particular application, the most effective concentration of calcium-containing borate in the aqueous suspension depends upon such factors as the nature of the fuel to be treated, the detailed manner of application and the amount and type of stabilizing agent, if any, that is included in the composition. Under most practical conditions the preferred compositions contain from about 3 to about 8 pounds of calcium-containing borate per gallon of water. It is often convenient, however, to make up a stock suspension containing a relatively large concentration of solid ingredients, for example, from 8 to 20 pounds per gallon of

water, and to dilute that stock solution with water to increase its fluidity before actual use.

Any convenient mixing procedure may be employed in preparing the aqueous suspension of borate. Measured quantities of water and of dry granular ingredients may be added to a mixing tank provided with any suitable automatic agitating means. Such means may comprise, for example, a paddle-type agitator or a centrifugal pump with a by-pass connection from the pump outlet back to the bottom of the tank. The resulting mixture is stirred until a uniform suspension is obtained. It is preferred to include a suitable agent to render the suspension stable, so that, once mixing is completed, agitation may be stopped, at least until just before the suspension is to be used.

The aqueous suspension may be distributed over the fuel surface in any convenient manner. Application by spraying is particularly rapid, effective and economical when the fuel to be treated is reasonably accessible. It is preferred to utilize a type of nozzle that produces a fine spray, one such nozzle being known as a "Bean" spray gun. A pump pressure of about 100 to 200 pounds per square inch is preferred, but effective coverage can usually be obtained with much lower pressures such as are typically available with fully portable equipment. When suitable power pumps are available, a nozzle opening of about $\frac{3}{16}$ inch has been found effective and will typically deliver from 4 to 8 gallons of suspension per minute.

30 The compositions of the invention are also particularly well suited for aerial distribution. For example, an aircraft of the type employed for spraying crops may be fitted with tanks having a valve-controlled outlet of large diameter, typically 6 to 24 inches, for rapid dumping of a tankful of suspension in a definite selected location in the path of a fire. After release into the air, the suspension has been found to break up typically into relatively fine drops, and is capable of penetrating effectively even into thick brush and of giving excellent coverage of fuel surfaces.

Where the fuel is accessible for spray treatment, dry grass and light to medium brush of the type commonly found in the lower hills of Southern California may be effectively treated in most instances by applying to the vegetation on each 100 square feet of ground surface from about 10 to about 20 pounds of calcium-containing borate in the form of an aqueous suspension per 100 square feet of ground surface. By such application strips of treated fuel of suitable width may be prepared, extending across the path of the fire. The most advantageous width for such strips varies with such factors as the detailed nature of the fuel, the slope of the ground and the amount and direction of the wind. It has been found, in general, that a fire can be effectively checked by so treating a strip of about the same width that would be required if the ground were completely cleared of vegetation. Thus a strip 4 to 6 feet wide is usually sufficient to check a fire on level ground in absence of wind, whereas a strip 6 to 8 feet wide or more may be preferable under less favorable conditions. Backfiring has been successfully carried out from a strip 2 to 4 feet wide treated as described by crews moving through grass and light brush at a fast walk.

When trees or clumps of tall brush occur inside a fire line of the described type, it is desirable to treat the surface fuels at the base of the trees and also the lower part of each crown. For example, scrub oak treated in that manner typically does not ignite and "crown out," whereas untreated trees of the same type burn readily, producing a serious source of spot fires.

70 Suspensions of calcium-containing borate can be rendered stable for an indefinite period by providing a suitable stabilizing agent. A preferred type of stabilizing agent comprises a finely divided inorganic solid which is chemically inert with respect to the borate and which

renders the solution thixotropic. Clays of the montmorillonite group are particularly useful as stabilizing agents for the present purpose. Illustrative of such clays are hectorite and Wyoming bentonite. Such clays may be combined with calcium-containing borate, such as ulexite, colemanite, or a mixture of the same, in a ratio of clay to borate of from about 1:20 to about 1:4 to give the borate suspension a useful degree of stability. Effective stability may also be produced, for example, with a type of clay that is commonly available under the trade name "Aquagel." A further example of a useful stabilizing agent is the insoluble gangue portion of the natural ore already referred to as C ore. That gangue comprises primarily a shale that tends to break down on wetting into a fine clay. Because of that action of the insoluble component, finely divided C ore may be suspended directly in water without other additive to produce a suspension that is remarkably stable and effective over a wide range of concentrations.

Stabilizing agents of the type just described have the particular advantage that, upon drying of the composition after application to the fuel, they act as a binder which tends to improve the uniformity and durability of the coating that is produced. By thus improving the physical nature of the coating layer, stabilizing agents of the described type contribute appreciably to the practical effectiveness of the treating compositions. That indirect action, however, is to be clearly distinguished from the direct fire retarding action of the solid calcium-containing borate, which preferably comprises the major portion of the coating layer.

Further additives may advantageously be included in the compositions of the invention. For example, it is sometimes desirable to provide a minor proportion of a wetting agent to promote uniform wetting of the fuel surface by the aqueous borate suspension. Such enhancement of the wetting qualities of the composition tends to produce a more uniform and continuous coating of the fuel. It may also be extremely helpful in obtaining effective penetration of the suspension to portions of the fuel that are partially hidden or enclosed, for example penetration into thick brush or into a thick covering of litter on the ground. Useful wetting agents for such purposes include, for example, aryl alkyl sulfonates, which are available under such trade names as "Oronite D-40" and "Petro P."

Adherence to the fuel of the film of solid calcium-containing borate may be further increased by including in the composition a suitable minor proportion of a sticking agent, such as the animal protein material sold as a commercial sticking agent under the trade name "Armour's Sticker"; the long-chain fatty acid preparation with diethylene glycol abietate which is available under the trade name "DuPont Spreader and Sticker"; or the lignin sulfonate which is available under the trade name "Orazan." From about 1 to about 10% of such sticking agents may be desirable. The duPont preparation also acts as wetting agent and has the particular advantage of not interfering with normal stability of the suspensions.

The compositions of the present invention are well adapted for application to the fuel in the form of a foam. A suitable foam, consisting of a mass of very small bubbles of the fluid composition, may be produced by adding to the herein described compositions an effective amount of a suitable foaming agent, and applying the composition to the fuel by spraying from a known type of foam-producing nozzle. From about 1 to about 3% of a conventional foaming agent has been found to be effective under most conditions.

Application of the compositions of the invention as a foam tends to promote their adherence to certain types of fuel which have an unusually smooth or waxy surface, such, for example, as the leaf surfaces of Manzanita brush. Moreover, the foam can be built up on the fuel to a considerable thickness without consumption of an undue amount of material. It has been found particular-

ly effective under some conditions to include a foaming agent in compositions for application by aerial drop. Upon release from the aircraft the suspension then becomes a light, fluffy and expanded material capable of covering a relatively large area.

The following particular compositions are described as illustrations of the wide variety of compositions within the scope of the invention. However, that scope is not intended to be limited by particulars of the illustrative examples, but is defined by the appended claims.

Example 1.—An illustrative and highly effective composition in accordance with the present invention was prepared by grinding ulexite to a particle size such that substantially 80% passed a 200 mesh screen and suspending the finely divided ulexite in water at a concentration of 4 pounds of ulexite per gallon of water. The resulting suspension was effectively stable for periods of the order of one hour, and could be maintained fluid for longer time periods by mild agitation. Compositions containing from about 3 to about 8 pounds of ulexite per gallon of water are also highly satisfactory.

Example 2.—Finely divided ulexite of the type employed in Example 1 was added to water in combination with clay of the type known as hectorite in typical proportions of about 3.5 pounds of ulexite and 0.5 pounds of hectorite per gallon of water. After thorough mixing, the resulting composition was a readily pourable but slightly viscous suspension which was highly stable and could be stored for several days without significant settling.

Example 3.—Colemanite was ground to predominantly pass a 200 mesh screen and was suspended in water in a concentration of 4 pounds per gallon of water. The resulting suspension was similar to that of Example 1. Colemanite may also be employed at concentrations from about 3 to 8 pounds per gallon of water. The stability of such suspensions can be greatly increased by addition of a stabilizing agent of the described type, for example hectorite, in a ratio of about 0.05 to 0.2 pound of agent per pound of colemanite.

Example 4.—A particularly economical and convenient composition consists essentially of an aqueous suspension of finely ground Shoshone ore, already described. For example, such ore was ground to a particle size predominantly minus 200 mesh and stirred in water at concentrations of about 3 to about 8 pounds per gallon of water, the preferred value being approximately 4 pounds per gallon of water. The resulting suspensions were highly stable and could readily be handled by hydraulic methods.

Example 5.—Ulexite and colemanite were finely ground and suspended in water in a ratio of approximately 5 pounds of ulexite and 2 pounds of colemanite per gallon of water. Stability of the resulting suspension is adequate for many purposes, but may be greatly increased by adding a stabilizing agent of the type described, for example a Wyoming bentonite, in a ratio of from about 0.05 to about 0.2 pound of the agent per pound of the other solid ingredients.

60 All of the compositions illustratively described in Examples 1 through 5 give satisfactory surface coverage on many types of fuel. Under certain conditions that action may be further improved by the use of further additives, as has already been described.

65 An indication of the effectiveness of the compositions of the invention was obtained by assembling a pile of cut dry brush approximately 12 feet in diameter and 6 feet high. The downwind half of the pile was then sprayed with the composition of Example 4 in sufficient quantity to coat substantially all exposed surfaces of the fuel. Evaporation of the water left the fuel coated with a hard dry solid film consisting essentially of calcium-containing borate. The untreated half of the brush pile was then set on fire. The untreated brush burned hotly and was substantially consumed in a few minutes. Most

of the treated brush remained unburnt. The compositions illustratively described in the other examples are similarly effective in checking the spread of fires.

I claim:

1. A composition for coating surfaces of fuel in the path of a fire to retard the same, said composition consisting essentially of an aqueous suspension of finely divided solid calcium-containing borate in a concentration between about 3 and about 20 pounds of said borate per gallon of water.

2. A composition as defined in claim 1, and in which the solid calcium-containing borate consists essentially of ulexite.

3. A composition as defined in claim 1, and in which the solid calcium-containing borate consists essentially of calcium borate and sodium-calcium borate in a weight ratio of approximately 2 to 5.

4. A composition as defined in claim 1 and in which the solid calcium-containing borate is predominantly finer than about 50 mesh.

5. A composition for coating surfaces of fuel in the path of a fire to retard the same, said composition consisting essentially of an aqueous suspension containing from about 3 to about 20 pounds per gallon of water of solid finely divided solid calcium-containing borate and containing also a finely divided substantially insoluble solid stabilizing agent in a concentration between about $\frac{1}{20}$ and about $\frac{1}{4}$ that of said borate, said stabilizing agent rendering the suspension stable and thixotropic.

6. A composition for coating surfaces of fuel in the path of a fire to retard the same, said composition consisting essentially of an aqueous suspension of a finely divided natural ore in a concentration between about 3 and about 20 pounds per gallon of water, said ore consisting essentially of sodium borate, sodium-calcium borate and insoluble gangue.

7. A composition for coating surfaces of fuel in the path of a fire to retard the same, said composition consisting essentially of an aqueous suspension containing between about 3 and about 20 pounds per gallon of water of a finely divided solid borate composition comprising sodium oxide, calcium oxide and boron trioxide in overall relative proportions approximating 1:3:8, respectively, by weight.

8. The method of retarding fire in solid fuel that has an exposed surface; said method comprising forming on a major portion of the fuel surface a substantially continuous adherent layer consisting essentially of solid calcium-containing borate.

9. The method of retarding fire in solid fuel that has

5 50

an exposed surface; said method comprising forming on a major portion of the fuel surface a substantially continuous adherent layer of solid material selected from the class consisting of calcium borate and sodium calcium borate.

10. The method of retarding fire in solid fuel that has an exposed surface; said method comprising forming on a major portion of the fuel surface a substantially continuous adherent layer of a natural ore consisting essentially of calcium borate, sodium-calcium borate and insoluble gangue.

11. The method of retarding fire in solid fuel that has an exposed surface; said method comprising distributing over the fuel surface an aqueous suspension of solid granular calcium-containing borate, the particle size of said borate being predominantly finer than about 50 mesh, and the rate of application of the suspension being sufficient to produce, upon evaporation of water therefrom, a solid coating over a major portion of the fuel surface.

12. The method of retarding fire in solid fuel that has an exposed surface; said method comprising distributing over the fuel surface an aqueous suspension of granular natural ore consisting essentially of calcium borate, calcium-sodium borate and insoluble gangue, the particle size of the ore being predominantly finer than about 50 mesh, and the rate of application of the suspension being sufficient to produce, upon evaporation of water therefrom, a solid coating over a major portion of the fuel surface.

13. The method of retarding fire in solid fuel that has an exposed surface; said method comprising distributing over the fuel surface an aqueous suspension containing between about 3 and about 10 pounds per gallon of water of a finely divided solid borate composition comprising sodium oxide, calcium oxide and boron trioxide in overall relative proportions approximating 1:3:8, respectively, by weight, the rate of application of the suspension being sufficient to produce, upon evaporation of water therefrom, a solid coating over a major portion of the fuel surface.

14. The method defined in claim 11 and in which the said aqueous suspension is distributed over the fuel surface in the form of a foam.
